United States Patent Office.

LUCRETIA E. SALLEE, OF PEORIA, ILLINOIS.

Letters Patent No. 79,148, dated June 23, 1868.

IMPROVEMENT IN LEATHER-WORK ORNAMENTS.

The Schedule referred to in these Letters Patent and making part of the same.

TO ALL WHOM IT MAY CONCERN:

Be it known that I, LUCRETIA E. SALLEE, of the city and county of Peoria, in the State of Illinois, have invented a new and improved Mode of Imitating Doll-Heads, Carved Work, Flowers, and other Kinds of Ornamental Work; and I do hereby declare that the following is a full, clear, and exact description of the manner of making the same, reference being had to the accompanying drawings, making a part of this specification.

The nature of my invention consists in imitating the form of doll-heads, carved work, flowers, and other kinds of ornamental work, by means of leather, untanned hide, gutta percha, or other flexible material, properly pressed in suitable moulds to obtain the form desired, in combination with a cement compounded of isinglass and shellac, thickened with finely-pulverized sand, to give the proper set or backing to the form that may be thus made, so as to prevent the same from being easily broken by falls or other violence that may happen to them.

To enable any one skilled in the art to make and use my invention, I will proceed to describe its construction. I first make a mould or moulds of metal to suit the kind of work I desire to imitate. A piece of leather is then cut to fit the mould. It is then soaked in water until it is sufficiently soft and pliable, when it is laid within the several cavities of the mould, and pressed and forced into them, so that it may conform fully to all the lines and curves therein, until the exact impression of the form has been taken.

Isinglass and shellac are next dissolved, and the liquid thickened with finely-powdered sand until the same is of the proper consistency, when it is immediately poured or brushed upon the back of the material in the mould in sufficient quantity to hold the same in shape.

After the cement has become hard, which it will in a short time, from its exposure to the air, the article thus made may be removed from the mould, and the same painted, bronzed, or varnished, as may suit the taste of the maker.

Having thus fully described my invention, what I claim therein as new, and desire to secure by Letters Patent, is—

The combination of the cement with the leather, untanned hide, gutta percha, and other flexible material, when formed substantially in the manner and for the purposes as herein described.
